REEL.

1,425,076.

Specification of Letters Patent. Patented Aug. 8, 1922.

Application filed December 29, 1920. Serial No. 433,776.

To all whom it may concern:

Be it known that I, CHARLES D. CATE, of Syracuse, in the county of Onondaga, in the State of New York, have invented 5 new and useful Improvements in Reels, of which the following, taken in connection with the accompanying drawings, is a full, clear, and exact description.

This invention relates to certain improvements in reels for sheet metal tape which is 10 usually furnished in tightly wound coils of predetermined length bound together by wires to hold the convolutions against expanding.

15 These tapes are fed from the reel into a suitable metal stamping machine where they are cut into rather small pieces for various articles of manufacture and the main object of my present invention is to permit bound 20 coils of various widths to be easily and quickly inserted in the reel of supporting frame and properly held in place preparatory to cutting the bonds and feeding the tape into the metal stamping machine without 25 liability of displacing the several convolutions axially one from the other, thus permitting the reel to be properly aligned with the machine to assure the direct and free feed of the tape thereto.

30 Another object is to provide simple and efficient means whereby the reel supporting frame may be adjusted to receive different widths of coiled tape.

A further object is to provide means for 35 limiting the circumferential distension or expansion of the coil after the bonds are cut with the tape coil in its supporting frame.

40 Other objects and uses relating to specific parts of the device will be brought out in the following description.

In the drawings:

Figure 1 is a front face view of a sheet metal tape reel embodying the various features of my invention except that the support for the reel supporting frame is 45 omitted.

Figure 2 is a longitudinal vertical sectional view of the same reel taken on line 50 2-2, Figure 1, the support being shown by dotted lines as partly broken away.

Figure 3 is an enlarged detail sectional view taken on line 3-3 Figure 1.

As illustrated this reel comprises a relatively 55 stationary main supporting frame 1,

relatively movable frame —2—, a rotary tape supporting drum —3—, a supporting spindle —4— for the drum, stops —5— on the main frame for limiting the expansion of the coiled tape as "A" and suitable means 60 for adjusting the movable frame —2— relatively to the main supporting frame —1— for receiving drums —3— and tapes "A" of different widths.

The main supporting frame —1— consists 65 of a pair of bars —6— and —7— crossing each other at substantially right angles midway between their ends and preferably recessed or halved one into the other at their crossings where they are rigidly secured together by gluing or any other fastening means.

A circular disk —8— of greater diameter than the normal diameter of the tape coil "A" is rigidly secured by screws —9— or 75 other fastening means to the inner or front face of the bars —6— and —7— and constitutes a part of the main supporting frame —1— which in this instance is disposed in a vertical plane. 80

The center of the disk —8— is substantially co-incident with the centers of the crossing portions of the bars —6— and —7— which together with the said disk are provided with a journal opening —10— for 85 the reception of the drum supporting spindle —4—. The frames —1— and —2— and also the drum —3— are preferably made of wood for economy of manufacturing, although it is evident that they may be made of any 90 other suitable material and that the cross bars —6— and —7— and disk —8— may be made in one piece if desired.

A metal plate —11— is centrally secured to the back of the frame —1— and is provided with a threaded hub —12— to which may be attached an upright supporting standard —13— shown by dotted lines in Figure —2— said standard having a base —14— adapted to rest upon the floor or other 95 support to hold the reel in proper alignment with the machine to which the metal tape is to be fed.

The horizontal cross bar —6— is preferably of substantially the same length as the 100 diameter of the disk —8— while the vertical bar —7— extends some distance below and above the adjacent edges of the disk to receive and support portions of the adjusting and holding means for the movable 110

frame —2— as will here-in-after be more fully described.

The lower end of the bar —7— is reinforced by metal wearing plates —15— secured to opposite sides thereof and together with said plates is provided with a transverse journal bearing —7'— and parallel guide opening —19— for receiving the adjacent end of an adjusting screw —18— and 10 a pair of guide pins —19— at opposite sides of the adjusting screw as shown in Figure —3—.

The movable frame —2— preferably consists of a horizontal bar —16— and a vertical bar —17— crossing each other substantially midway between their ends at right angles to each other and like the bar —6— and —7— are recessed or halved one into the other at their crossings where they are glued or otherwise secured one to the other, the horizontal bar —16— being of approximately the same length as the diameter of the disk —8— while the vertical bar —17— extends some distance below and above the 25 corresponding edges of said disk.

The vertical bars —7— and —17— of the frames —1— and —2— are disposed in the same longitudinal vertical plane and, therefore the bars —6— and —16— are disposed 30 in substantially the same lengthwise horizontal planes, the center of the movable frame —2—, being substantially co-incident with the axis of the disk —8— and is provided on its inner face with a central recess 35 —4'— for receiving the head of the pivotal bolt —4— as shown in Figure —2—.

The lower end of the upright bar —17— of the movable frame is reinforced by a metal plate —20— which forms one of the 40 sections of a hinge —21—, the other section of which is secured to a nut —22— which is engaged by the screw —18—, the hinge —21— serving as a means by which the frame —2— may be rocked toward and 45 from the frame —1— while the screw —18— serves as a means for adjusting the frame —2— toward and from the frame —1—, said screw being arranged in a horizontal position at the bottom of the reel where it is easily accessible for adjustment 50 and has its rear end journaled in the lower end of the bar —7— and held against endwise movement by shoulders —23— and —24—, Figure —2—.

55 The guide pins —19— are secured to the nut —22— at opposite sides of the screw —18— and extends through the guide openings —19— in the lower end of the bar —7— to support the nut and to assist in 60 guiding the frame —2— in its movement toward and from the frame —1— and also to hold said frame —2— against lateral rocking movement. A spring catch —25— is secured at one end to the upper end of the bar —7— of the main frame —1— and ex-

tends forward over the top of the bar —17— of the movable frame —2— where it is provided with a series of apertures —26— for receiving a locking pin —27— on the upper end of the bar —17— to hold the frame —2— in its various positions of adjustment when the reel is adjusted for use.

The tape coil "A" is generally wound in such a manner as to form a central opening for the reception of a drum as —3— which is adapted to fit easily within the said opening even when the coil is bound by tie wires as "a", the face width of the drum being substantially equal to the width of the tape so that when the drum is placed within the 80 central opening of the coil its opposite faces will be substantially flush with the corresponding faces of said coil.

The drum —3— is provided with a central opening for receiving the bolt or spindle —4— which is slidable endwise in said opening and also in the opening —10— and the frame —1— so that it may be readily removed when the movable frame —2— is unlocked and rocked forward toward the 90 position shown by dotted lines in Figure —2—.

The stops —5— are arranged circumferentially around and upon the front face of the disk —8— in equally space relation 95 and preferably consists of rollers for limiting the outward expansion or extension of the tape coil "A" when the bonds "a" are cut and also affording anti-friction bearings for the tape as it is withdrawn from 100 the reel against one or the other of the stops as shown by dotted lines in Figure —1—.

Operation.

In the operation of my device the drum 105 as —3— having a face width corresponding to the width of the tape to be reeled is placed in operative position, coaxial with and against the front face of the disk —8— and the pin —4— is then inserted in the 110 opening —10— to hold the drum in place, it being understood that during this operation the movable frame —2— is rocked forwardly toward the dotted position or sufficiently to permit the placing of the 115 drum and pin and that the frame —2— has been adjusted by means of the screw —18— and catch —25— to form an intervening opening or space between the two frames corresponding to the thickness of 120 the drum or width of the tape.

The tape coil with the bonds "a" still in operative positions thereon are then placed over and upon the periphery of the drum —3— and against the front face of the disk —8— whereupon the frame —2— is closed and locked in place by the catch —25— to confine the coil on the drum between the two frames after which the bonds "a" may be cut to allow the coil to expand against the 130

stops —5— and permit the free end of the coil to be drawn into the machine which is to operate upon the tape.

If another tape of widely different width 5 is to be used, a different drum —3— of corresponding width would be selected to support the coil while the frame —2— would be adjusted by means of the screw —18— and the catch —25— to correspond to the, 10 width of the drum and tape.

By extending the head of the bolt —4— into the socket —16— of the frame —2— it enables the bolt to be supported at both ends to carry the weight of the drum —3— 15 and tape coil thereon.

The device described not only expedites the work of installing the tape coils in the reel-frame before cutting the bond but also assures the retention of the convolutions of 20 the coil within operation limits after the bonds have been released all of which greatly increases the output of work by avoiding the usual delays in replacing the coils in the reel.

25 What I claim is:

1. In a device for holding coiled material, the combination of a main frame, a coil-supporting drum rotatably mounted on said frame wholly within the marginal edges 30 thereof, a spindle journaled at one end in said frame beyond the periphery of the drum and having its other end threaded and extended across said periphery, a nut engaged with the threaded end of the spindle 35 for axial adjustment thereon, a movable frame hinged to said nut for axial and tilting adjustment toward and from the main frame, and a catch for locking and releasing the movable frame in and from its closed 40 position.

2. In a device for holding coiled material, the combination of a main frame, a coil-supporting drum rotatably mounted on said frame wholly within the marginal edges 45 thereof, a spindle journaled at one end in said frame at one side of the drum and parallel with the axis thereof and having its other end threaded, a nut engaged with said threaded end for axial adjustment thereon, 50 a movable frame hinged to said nut to move axially and to tilt toward and from the main frame, and catch means on said frames at the opposite side of the drum for locking and releasing the movable frame in and from its 55 closed position.

3. A reel comprising a relatively stationary main supporting frame, a screw spindle journaled in said frame, a nut engaged with the screw for adjustment lengthwise thereof 60 as the screw is turned, a relatively movable frame hinged to the nut to swing toward and from the main frame, means for holding the movable frame in its adjusted position, and means for supporting a tape coil be- 65 tween the frames.

4. In a device for holding coiled material, the combination of a main frame having means on one side for attachment to a support and its opposite side provided with a flat bearing face for alining the edges of a 70 coil, a drum rotatably mounted on the frame adjacent said bearing face and wholly within the marginal edges thereof, stop pins projecting from said bearing face across the periphery of the drum in radially spaced relation thereto, a spindle journaled on the frame at one side of the drum and provided with a threaded end projecting across the periphery of said drum, a nut engaged with said threaded end for axial adjustment 75 thereon, and a movable frame hinged to said nut for tilting and axial movement relatively thereto and toward and from the main frame, and means at the opposite side of the drum for locking and releasing the movable frame 80 in and from its closed position.

5. In a device for holding coiled material, a main frame composed of bars crossing each other at right angles, and a circular plate secured to the inner faces of said bars to form 90 a back-rest for the adjacent edges of the coil, in combination with a coil-supporting drum concentric with the circular plate and adjacent the inner face thereof, stop pins projecting from the circular plate across 95 the periphery of the drum in spaced relation thereto and in uniformly spaced relation circumferentially, a threaded spindle journaled in the outer end of one of said bars and extending across the peripheries of the said 100 circular plate and drum, a nut engaged with the threaded portion of the spindle, a supplemental frame hinged to the nut for tilting movement toward and from the first named frame, and catch means between said 105 frames for holding the movable frame in its operative position across the outer end of the drum.

6. In a device for holding coiled material, a pair of normally coaxial frames movable 110 axially one in relation to the other, a spindle coaxial with said frames and having one end enlarged and seated in a corresponding socket in the inner face of the movable frame and its other end extended loosely through 115 an opening in the relatively stationary frame, means for adjustably supporting the movable frame in a plane parallel to but apart from that of the main frame, a drum journaled on the spindle between the frames 120 for supporting the coil, and stop pins projecting from the main frame across the periphery of the drum in spaced relation thereto and in uniformly spaced relation circumferentially thereof.

In witness whereof I have hereunto set my hand this 18th day of December, 1920.

CHARLES D. CATE.

Witness:

H. E. CHASE.
